UNITED STATES PATENT OFFICE

170,739

DENTAL ABRADING UNIT

Robert Corson Angell, Prince Bay, N. Y., assignor
to The S. S. White Dental Manufacturing Com-
pany, a corporation of Pennsylvania

Application January 26, 1951, Serial No. 13,992

Term of patent 14 years

(Cl. D24—1)

To all whom it may concern:

Be it known that I, Robert Corson Angell, a citizen of the United States, and a resident of Prince Bay, county of Richmond, State of New York, have invented a new, original, and ornamental Design for a Dental Abrading Unit, of which the following is a specification, reference being had to the accompanying drawings, forming part thereof.

Fig. I is a perspective view showing the front, top and one side of a dental abrading unit embodying my new design. The other side is like the side shown; and

Fig. II is a top perspective view thereof on an enlarged scale.

I claim:

The ornamental design for a dental abrading unit as shown and described.

ROBERT CORSON ANGELL.
